VOICE CURRENT REPEATER CIRCUITS

Edward Kenneth Sandeman, Philip Robert Thomas, and Carlton Rosslyn Dunham, London, England, assignors to International Standard Electric Corporation, New York, N. Y., a Corporation of Delaware

Application October 3, 1930, Serial No. 486,130,
and in Great Britain October 19, 1929

8 Claims. (Cl. 179—170)

This invention relates to telephone communication systems in which one-way amplifying devices are employed for strengthening the telephone currents transmitted thereover and the object of the invention is to provide a means whereby when transmission is required in a certain direction, the repeaters are switched into condition for repeating in that direction and when a change of transmission is desired, an automatic change in the repeater connections is made so that transmission may take place in the other direction with the desired amplification.

According to one feature of the invention, the telephone signals are repeated over a circuit arrangement between two two-wire lines, the said circuit arrangement being adapted to provide repeater paths over either one of two branch circuits, the arrangement being such that neither branch circuit is normally connected with both said two-wire lines, switching means being provided and adapted to control the connections of the two-wire lines to both input and output terminals of the branch circuits.

According to a further feature of the invention, the connecting of the branch circuit between the said two two-wire lines is effected by an incoming telephone current which is adapted to be amplified over said branch.

Other features of the invention will be disclosed in the following description having reference to the accompanying drawings, in which:

Fig. 1 illustrates schematically one embodiment of the invention.

Fig. 2 illustrates a modification of the arrangement shown in Fig. 1.

Fig. 3 shows in more detail the construction of a relay which may be used in the circuit arrangement of Figs. 1 and 2.

Fig. 4 shows an embodiment of the invention in which a one way repeater is used for amplifying currents in both directions of transmission.

Fig. 5 is a modification of Fig. 4.

Fig. 6 is a still further modification of the arrangement shown in Fig. 4.

Fig. 1, W and E represent the points at which the circuit, in which amplification is required, enters the amplifier station. 1, 2, 3 and 4 are one way amplifying devices, the direction of amplification being indicated by the arrows. 5 and 6 are amplifier detectors which cause operating currents to flow respectively through the coils 7 and 10 of the relays 11 and 14, when speech voltages of the necessary amplitude are applied to their inputs. 15 is a delay network having a characteristic impedance which is sub-

stantially a pure resistance. 16 and 17 are three winding transformers, known in the art as hybrid coils. 18 and 19 are resistances equal to the characteristic impedance of the delay network. The hybrid coils are wound in a known manner so that currents in the output of amplifier 1 apply no currents or only attenuated currents to the input of 4 and in the output of amplifier 3 apply no current or only attenuated currents to the input of 2. The normal or un-operated position of the contacts of relays 11 and 14 is as shown.

In the non-operated position of the relays the system, as shown on the schematic, is stable and free from oscillation because there is no complete back coupling path from the output to the input of any amplifier or cascade combination of amplifiers. It is assumed that capacity, through the relay 11, between the output of amplifier 4 and the input of amplifier 1 is effectively eliminated. Similarly, capacity, through relay 14, between the output of 2 and input of 3 is effectively eliminated. Means for accomplishing this are described below.

The method of operation is as follows:

Speech currents arriving at W pass through amplifier 1 and are simultaneously applied to the input of the detector amplifier 6 and the delay network 15. The effect of the currents entering the detector 6 is to operate the relay 14 so that the output of amplifier 2 becomes connected to the line E before the currents traversing the delay network reach the output of 2. The time delay of the delay network must therefore be made greater than the operating time of the relay 14. In this way speech currents arriving at W are amplified by 1 and 2, and pass out to E. The process of switching the line E from the input of 3 to the output of 2 also prevents speech currents coming from the other direction from affecting the switching gear and gives the control of the line to the speaker applying speech at W.

By a similar train of operations speech arriving from E is passed out at W, the speaker applying speech to E retaining control of the line.

Speech entering at W is at a sufficiently high level to operate the detector amplifier 6, but is so attenuated by the delay networks and hybrid coils that it is not at a sufficiently high level to operate detector amplifier 5. The converse is evidently true for speech entering at E.

The second arrangement differs from the first by the fact that the two hybrid coils are each replaced by a relay (12 or 13 Figure 2), worked by the output of the corresponding detector-

amplifier, in parallel with the relays 11 or 14. The effect of the four relays is that the two second stage amplifiers 2 and 4 are disconnected, and no through conversational circuit exists, until 5 the arrival of speech currents results in the operation of two of the 4 relays. Thus in the normal or unoperated condition the device is evidently stable. Speech currents arriving at W, are amplified by 1 and pass to the delay network 10 15, and also to the output of the detector-amplifier 6 which causes the operation of relays 13 and 14. The time of operation of these relays is arranged to be less than the "delay" of 15, so that by the time the network is traversed by the speech 15 current the relays have operated, and the amplifier 2 is switched in to connect the delay network to the line E. The relay 14 when operated prevents speech in the direction E—W taking place before that in the W—E is finished, and relay 13 20 prevents the speech currents from the delay network reaching detector amplifier 5. In the operated condition the device is thereby stable and it also acts as an echo "suppressor".

A similar train of operations, provides for 25 speech entering at E to be amplified to the line W. As in the first arrangement it is necessary, in order to avoid oscillation, that there be only small capacity coupling between amplifiers 1 and 4, and 2 and 3.

30 Fig. 3 indicates a method of construction of relays 11, 12, 13 and 14 by which this capacity can be reduced as far as possible.

The general construction of the relay armature 26 and coil 27 is the usual construction, but 35 the contact springs 21 and 23 to which the leads to one amplifier, and 22 and 24 to which the leads to the other amplifier are attached are screened in pairs. The springs 20 and 25 make contact with 21, 22, 23 and 24 through small holes in the 40 screens. The leads from the amplifiers are made with screened wire, the covering of which together with the screens on the relays are connected to some suitable earthing point.

45 In Fig. 4 one amplifier may be used for amplifying in both directions of transmission and by this means an economy may be effected since it is clear that as conversation can take place only in one direction at any instant, there need be only one power amplifier, provided that switching 50 means are arranged in accordance with the above principles.

In Fig. 4, 31 and 32 are the two first stage amplifiers and 33 the common power amplifier. Speech currents arriving at W are amplified by 31 and 55 pass to 34, a suitable delay network. The input of an amplifier detector 35 is taken from the penultimate stage of amplifier 31, and the output operates relay 37, on the arrival of speech currents at W. Relay 37 disconnects line E from 60 its first stage amplifier and connects it to the output of the power amplifier. Thus by the time the speech currents have traversed the delay network, relay 37 has operated, and the conversational circuit for the direction W—E is made. Whilst 65 speech is travelling in this direction relay 37 remains operated and speech in the opposite direction is rendered impossible and echo thereby suppressed. The speaker at the W end retains control of the circuit. When relay 37 is again normal speech in the direction E—W can take place, and results in a similar train of operations.

70 Provided that capacities in relays 37 and 38 are reduced to a minimum by means such as were described above, there is no singing circuit and 75 the device is stable both in the normal and in

the operated condition. It is necessary that the input of 36 be not taken from the last stage of 80 32, but from some intermediate stage. By this means it is prevented from operating relay 38 when conversation is in the direction W—E, which it would do were it connected to the last stage of 32. A similar remark applies to the detector 85 amplifier 35.

Fig. 5 shows a similar device containing four relays, two 39 and 40 worked by detector 45 and 90 two 43 and 44 by detector 46. The arrival of speech voltages at W results in the operation of 95 39 and 40, by which the input of the common power amplifier 43 is connected to the further end of the delay network 41 and the output to the line E. As before the input of 46 is taken from some intermediate stage of amplifier 42 so that the operation of relays 43 and 44 during conversation W—E is prevented. The same remarks concerning control, stability and echo suppression, as in Fig. 4 apply here.

Fig. 6 shows a variation of method of Fig. 5 in which the necessity of taking the inputs of the amplifier detectors from an intermediate stage of the first stage amplifiers is obviated. Speech currents arriving at W are amplified by 57, and 100 finding relay 54 normal pass into the delay network 51. By the time that the network is traversed, detector 55 has operated relays 49 and 105 50 and the speech currents pass via the power amplifier and to line E. The circuit to detector amplifier 56 is broken so that relays 53 and 54 are prevented from operating during conversation 110 W—E. The same remarks concerning control, 115 stability and echo suppression as in the above cases, also apply here.

As is now well known the electric charges in a conductor are in a state of thermal agitation, in thermodynamic equilibrium with the heat 120 motion of the atoms of the conductor. This phenomenon manifests itself as a fluctuation of potential difference between the terminals of the conductor and the effect produced in an amplifier, due to connection of the conductor 125 to the input side of the amplifier or to thermal agitation within the amplifier itself is known as "Johnson noise". For a more detailed description of the phenomenon reference may be had to the Physical Review, vol. 32, July 1928, page 130 97, and the Philosophical Magazine, vol. 7, 1929, page 774.

The arrangement shown in Fig. 6 is particularly advantageous in those cases where the 130 E. M. F. of thermal agitation in the amplifiers becomes important. In the arrangement shown in Figures 4 and 5 the delay network is subjected to noise from both amplifiers 31 and 32 and 47 and 42 respectively during both idle and talking 135 periods. In Fig. 6 either amplifier 57 or amplifier 52 is disconnected from the delay network thus only noise generated in the actual speaking circuit is transmitted through the delay network 51 and power amplifier 53.

This feature could be accomplished in arrangements similar to those shown in Figs. 4 and 5 by the provision of means to reduce the gain of the amplifier not required during speech. Relays operated simultaneously with relays 37 and 38 145 of Fig. 4 could be arranged to short circuit a convenient point in the amplifiers 32 and 31 respectively. The points of connection of detector amplifiers 35 and 36 to amplifiers 31 and 32 would be suitable for this purpose.

What is claimed is:

1. In a transmission system the combination of two lines each provided with switching mechanism, two branch circuits provided with two amplifiers, one branch circuit for each of said lines, a conversation path common to said lines including a delay net-work, means controlled over one of said lines for operating the switching mechanism of the second line through both of said amplifiers of one of said branch circuits, means controlled by said operated switching mechanism for connecting a third amplifier to the common conversation path, and means controlled by said delay network for retarding voice currents transmitted over the first mentioned line until after the operation of the switching mechanism of the second line. 80
- 10
- 15
2. In a transmission system the combination of two lines each provided with switching mechanism, two branch circuits provided with two amplifiers, one branch circuit for each of said lines, a conversation path common to said lines including a delay net-work, means controlled over one of said lines for operating the switching mechanism of the other line through both of said amplifiers of one of said branch circuits, means controlled by said operating switching mechanism for connecting a third amplifier to the common conversation path, means controlled by said delay net-work for retarding voice currents transmitted over the first mentioned line until after the operation of the switching mechanism of the second line, the operation of said switching mechanism serving to form a conversation path between both of said lines through one of said first mentioned amplifiers the delay net-work and third amplifier, the operation of the switching mechanism also serving to disconnect its associated line from its own branch circuit. 85
- 20
- 25
- 30
- 35
- 40
- 45
3. In a transmission system the combination of two lines each provided with switching mechanism, two branch circuits provided with two amplifiers, one branch circuit for each of said lines, a conversation path common to said lines including a delay network, means controlled over one of said lines for operating the switching mechanism of the other line through both of said amplifiers of a branch circuit, means controlled by said operating switching mechanism for connecting a third amplifier to the common conversation path, means controlled by said delay network for retarding voice currents transmitted over the first mentioned line until after the operation of the switching mechanism of the second line, the operation of said switching mechanism serving to form a conversation path between both of said lines through one of said first mentioned amplifiers the conversation path, the delay net-work and third amplifier. 90
4. In a transmission system two 2-wire lines, two branch circuits adapted to amplify in opposite directions, a switch which normally disconnects one 2-wire line from one branch circuit, another switch which normally disconnects the other 2-wire line from the other branch circuit each of said switches normally connecting a branch circuit with one 2-wire line, means whereby said switches may reverse the connections so as to control the connections to both the input and output terminals of said branch circuits and a delay network common to said branch circuits. 95
5. A transmission system according to claim 4 wherein the delay network is connected to the branch circuit over a hybrid coil. 100
6. A transmission system according to claim 4 wherein the delay network is connected to the branch circuits over two additional switches controlled one from each 2-wire line. 105
7. A transmission system according to claim 4 comprising two additional switches adapted to connect the delay network to the branch circuits wherein said additional switches operate under control of current from the input circuits of an amplifier in the branch circuits. 110
8. A transmission system according to claim 4 comprising two additional switches which normally connect the delay network to both branch circuits. 115
